UNITED STATES PATENT OFFICE.

ANTHONY FRICKER, OF LAKewood, OHIO.

CLASP.

Original application filed March 1, 1922, Serial No. 540,111. Divided and this application filed October 25, 1922. Serial No. 596,832.

To all whom it may concern:

Be it known that I, ANTHONY FRICKER, a citizen of the United States, residing at Lakewood, in the county of Cuyahoga and 5 State of Ohio, have invented certain new and useful Improvements in Clasps, of which the following is a specification.

This invention relates to clasps, such as are used for temporarily binding together 10 thick masses of paper sheets, files or the like, up to thicknesses of an inch or so.

This application is a division of my co-pending application for method of making clasps, filed March 1, 1922, Serial Number 15 540,111.

The object of the present invention is to provide a clasp of special improved form, which can be made from steel strips so that subsequent tempering operations are unnecessary; in which the clasping arms are so formed and are so disposed relative to the joining head that the clasp has maximum inherent spring tension with its arms lying truly parallel up to its maximum open position, and which clasp is strong and durable, 25 simple in construction and inexpensive to manufacture.

Further objects of the invention are in part obvious and in part will appear more in 30 detail hereinafter.

In the drawing, which represents one suitable embodiment of the invention, Fig. 1 is a perspective view of my improved clasp, and Fig. 2 is a side elevation thereof.

As illustrated in the drawing, the clasp is made from a single strip of steel of any suitable width and length, one clasp of satisfactory form being about three-quarters of an inch wide and approximately six inches long. 35 The head of the clasp, indicated generally at 1, is in the form of a loop or eye joining the two arms 2, which lie parallel and in contact over an appreciable portion of their length, due to the formation of the clasp in 40 a manner to impart inherent tension thereto, such that the normal position of the arms, if they could pass each other, would be at approximately right angles to each other. This effect is secured in the present clasp by 45 forming the eye 1 with two side bends 3 and an end bend 4, said bends being put into the metal of the tempered strip so that subsequent tempering is unnecessary.

As stated in my copending application before referred to, the side and end bends 3, 4

are formed in a manner to overbend the material, or in other words, to put into the clasp more initial tension than is necessary, after which one or more of the bends are partially straightened to take out a part of the tension and leave just the amount necessary to give the arms sufficient resiliency and holding ability and also keep them parallel in the various positions of the clasp up to full open position with the arms about an inch apart. 60 65

One of the arms 2 of the clasp is longer than the other, say approximately an inch longer, and the end of the shorter arm is flared outwardly, as at 5, so as to form a mouth adapted to readily receive the edges 70 of the sheets of paper, etc. to be inserted in the clasp.

An aperture 6 is also preferably provided in one side of the eye 1 or in the inner end portion of one of the arms 2, so that if desired, the clasp can be readily suspended in 75 vertical position.

It will thus be seen that I have provided a clasp of pleasing form and with material gripping tension between its two arms. It 80 can be clasped about a thick mass of papers with a good holding quality or ability throughout the length of the arms.

For convenience in illustration, the side and end bends in the head of the clasp have 85 been shown slightly exaggerated in the drawing.

What I claim is:

A metal clasp formed of a single thin flat spring strip of substantial width and bent to 90 form an intermediate curved portion from the ends of which extend two gradually converging arm portions which meet at a remote point and contact throughout a substantial portion of their length, the metal of 95 the clasp being provided with a transverse bend at the junction of the curved portion with each arm portion, said bends permanently setting the metal of the clasp so that the normal tendency of the arms, if moved out of aligned engagement, is to pass each other, and said curved portion being provided substantially midway its ends with a transverse bend which permanently sets the metal and gives the contacting arm portions 100 material and additional gripping tension. 105

In testimony whereof I hereby affix my signature.

ANTHONY FRICKER.
